[57] CLAIM

The ornamental design of the high chair tray, as shown and described.

DESCRIPTION

FIG. 1 is a top view of the high chair tray showing the design of our invention;

FIG. 2 is a bottom view thereof;

FIG. 3 is a front view thereof;

FIG. 4 is a rear view thereof;

FIG. 5 is a right side view thereof;

FIG. 6 is a perspective view, the broken lines are for environmental purposes only and form no part of the claimed design;

FIG. 7 is a perspective view thereof; and,

FIG. 8 is a cross-sectional view taken from line 8—8 in FIG. 4.

The left side view is a mirror image of the right side view.

FIG. 1

FIG. 3

FIG. 4
